UNITED STATES PATENT OFFICE.

EARLE S. LYON, OF NEW YORK, N. Y.

NON-GLARING HEADLIGHT.

1,261,570.

Specification of Letters Patent. Patented Apr. 2, 1918.

Application filed November 27, 1917. Serial No. 204,244.

To all whom it may concern:

Be it known that I, EARLE S. LYON, citizen of the United States, residing at New York, in the county of New York and State 5 of New York, have invented certain new and useful Improvements in Non-Glaring Headlights; and I do hereby declare the following to be a full, clear, and exact description of the invention, such as will enable others skilled in the art to which it 10 appertains to make and use the same.

My invention relates to non-glaring headlights and more particularly to that class of headlight used in connection with motor 15 vehicles and it has for its main object the provision of a simple and inexpensive device which may be easily detachably secured to a lamp, and which may be applied to any lamp of standard make.

Another object is to provide a novel and 20 improved attachment to headlights embodying a structure whereby the light rays are diffused, and their direct passage through the glass is reduced to a minimum, so that 25 an intense glare is entirely eliminated.

It is necessary, in order to accomplish 30 my purpose, that certain of the light rays which are transmitted through the lens be eliminated or diffused, as ordinances in force in various localities provide in effect 35 that no direct light rays shall be transmitted from a headlight, which will encounter the eyes of the driver of another vehicle or of a pedestrian at a certain distance from the 40 headlight. Therefore, another object of my invention is to provide a device which will accomplish the purpose stated, and will at the same time, be very economical in construction and convenient in application.

It will be obvious also that my invention 45 may be applied to light sources other than vehicle lamps, for the purpose of preventing glare.

A further object is to provide an improved shield adapted to be placed in front 50 of the source of light for preventing a blinding glare issuing from the lamp but permitting substantially the same amount of illuminating rays to emanate as in lamps not equipped with my improvement.

With the foregoing objects outlined and with other objects in view, my invention 55 consists in the novel features hereinafter

described in detail, illustrated in the accompanying drawing, and more particularly 55 pointed out in the appended claim.

Referring to the drawing:

Figure 1 is a sectional view through an ordinary headlight, showing one form of 60 my improved shield attached thereto.

Fig. 2 is a front view of one form of my shield.

Fig. 3 is a front view, partly broken away, of another form of my shield.

In the drawings, 1 designates an ordinary 65 headlight having a parabolic reflector 2, a source of light 3, a cover 4 and a lens 5. My improved shield 6 is preferably placed against the rear surface of the lens and forward of the source of light.

The shield shown in Figs. 1 and 2 consists of an opaque plate, preferably of metal, provided with a series of small apertures 7, preferably concentrically arranged, which in this instance, covers approximately 75 the entire area of the plate with solid portions of the plate between said apertures. The rear side 8 of the plate is highly polished and acts as an auxiliary reflector for causing a considerable part of 80 the light, reflected by the parabolic reflector of the lamp, to be reflected back to the parabolic reflector and finally find its way out through the small apertures 7 of the plate.

It will be seen that the apertured plate arranged in front of the parabolic reflector will diffuse the rays from said reflector and eliminate the dazzling glare, but in order 85 that the lamp may be as powerful as one without the shield, I have polished the rear face of the plate so that a large portion of the rays will be reflected back to the parabolic reflector and thus intensified, so that the light rays lost through the intervention of the shield, will not affect the illuminating 90 power of the lamp. By my improved shield I am enabled to obtain the same amount of 95 light from the lamp, without the dazzling or blinding glare.

Also by arranging the small apertures in 100 concentric circles with the solid portions between, I am enabled to diffuse the light from the parabolic reflector without appreciably diminishing its penetrating powers. The rays from a parabolic reflector are 105 thrown in a circle and my concentric ar-

angement of the apertures, will be efficient in thoroughly diffusing these rays and eliminating the glare.

The shield shown in Fig. 3, is exactly 5 the same as that shown in Figs. 1 and 2, with the exception that I have provided a large aperture 10 at the center of the shield and surrounded the same with a series of concentrically arranged apertures 11, which 10 are smaller in diameter than the aperture 10, and larger in diameter than the apertures 7. This form of shield while avoiding the blinding glare from the lamp, will permit intensified rays to pass unobstructed 15 through the central portion of the shield and provide greater illumination directly in line with the center of the lamp, than a lamp not provided with this form of shield.

I also preferably provide a dull finish on the front face 12, of the shields, so that 20 they will not reflect the sunlight during the daytime.

What I claim and desire to secure by Letters Patent is:—

The combination with a lamp having a 25 parabolic reflector, of an opaque shield arranged on one side of the lamp lens, and provided at its center with a large aperture, and between said aperture and the edge of the shield, with a series of concentrically arranged small apertures, said shield having its rear face polished to reflect a portion of the light rays back to the reflector for intensifying the same.

In testimony whereof I affix my signature. 35
EARLE S. LYON.
